UNITED STATES PATENT OFFICE.

MARTIN SCHROYER, OF BROWNSVILLE, PENNSYLVANIA.

TIE-PLATE AND RAIL-FASTENER.

1,074,472.

Specification of Letters Patent. Patented Sept. 30, 1913.

Application filed July 22, 1913. Serial No. 780,556.

To all whom it may concern:

Be it known that I, MARTIN SCHROYER, a citizen of the United States of America, residing at Brownsville, in the county of 5 Fayette and State of Pennsylvania, have invented certain new and useful Improvements in Tie-Plates and Rail-Fasteners, of which the following is a specification, reference being had therein to the accompanying 10 drawing.

This invention relates to a tie plate and rail fastener, and the primary object of my invention is to provide a novel plate that can be quickly secured to a tie to support the 15 base flanges of rails, whereby the tie is not worn or injured by wear and the great weight of rolling stock upon the same.

Another object of this invention is to provide a rail chair that has provision 20 whereby a rail mounted thereon cannot become longitudinally or vertically displaced.

A further object of this invention is to provide a tie plate and rail fastener that is simple in construction, durable, inexpensive 25 to manufacture, easy to install and highly efficient for the purposes for which it is intended.

I attain the above objects by a mechanical construction that will be hereinafter specifically described and then claimed, and reference will now be had to the drawing, 30 wherein:

Figure 1 is a plan of the tie plate and rail fastener, showing a rail in position, Fig. 35 2 is a plan of the detached tie plate, Fig. 3 is a side elevation of the same with a rail in position, Fig. 4 is a perspective view of a portion of the tie plate showing the fastener, and Fig. 5 is a side elevation of the same.

40 In the drawing the reference numeral 1 denotes a rectangular tie plate that is provided with transverse depending ribs 2 adapted to engage in the upper surface of a tie 3 and prevent the plate from sliding or becoming 45 accidentally displaced relatively to the tie.

The plate 1 provides a seat or chair 4 for the base flanges 5 and 6 of a rail 7. The base flange 5 engages the transverse brace 8 formed integral with the plate 1 and the 50 base flange 6 is scalloped or serrated, as at 9

to engage the scalloped or serrated edge 10 of a transverse brace 11 formed integral with the plate 1. The scalloped confronting edges of the flange 6 and the brace 11 prevent longitudinal movement of the rail upon 55 the tie plate and to prevent vertical displacement of said rail the braces 8 and 11 and the plate 1 have vertical openings 12 to accommodate spikes 13 that are driven into the tie. The spikes extend over the base 60 flanges 5 and 6 as best shown in Figs. 1 and 3.

Additional spikes 14 are driven through openings 15 provided therefor in the plate 1 in holding said plate in engagement with 65 the tie.

In Figs. 4 and 5 the transverse brace 11 is illustrated as having malleable lugs 16 and these lugs can be bent over onto the base flange 6 to coöperate with the spikes 13 in 70 preventing vertical displacement of the rail.

One embodiment of the invention has been illustrated but it is to be understood that the structural elements are susceptible to such variations and modifications as fall 75 within the scope of the appended claims.

What I claim is:

1. In a tie plate and rail fastener, the combination with a tie, and a rail having a scalloped flange, of a tie plate arranged 80 upon said tie and having depending ribs to engage in the upper surface thereof, a transverse brace carried by said plate and engaging one of the base flanges of said rail, a transverse brace carried by said tie plate 85 and having a scalloped edge engaging the scalloped base flange of said rail, spikes extending through said braces into said tie and having the heads thereof engaging the base flanges of said rail, and spikes extend- 90 ing through said plate into said tie.

2. In a tie plate and rail fastener, the combination with a tie, and a rail having a scalloped flange, of a tie plate arranged upon said tie and having depending ribs to 95 engage in the upper surface thereof, a transverse brace carried by said plate and engaging one of the base flanges of said rail, a transverse brace carried by said tie plate and having a scalloped edge engaging the 100

scalloped base flange of said rail, spikes extending through said braces into said tie and having the heads thereof engaging the base flanges of said rail, spikes extending through said plate into said tie, and malleable lugs carried by the scalloped brace of said plate and adapted to be bent onto the scalloped base flange of said rail.

In testimony whereof I affix my signature in the presence of witnesses.

MARTIN SCHROYER
